United States Patent Office.

WILLIAM LIDDELL, OF BOSTON, MASSACHUSETTS, ASSIGNOR TO B. S. BINNEY, OF SAME PLACE.

Letters Patent No. 96,125, dated October 26, 1869.

IMPROVEMENT IN MACHINE FOR MAKING TAGS.

The Schedule referred to in these Letters Patent and making part of the same.

To all whom it may concern:

Be it known that I, WILLIAM LIDDELL, of Boston, in the county of Suffolk, and State of Massachusetts, have invented a certain new and useful Improvement in Paper-Tag Machines; and I do hereby declare that the following is a full and exact description thereof, reference being had to the accompanying drawings, and to the letters of reference thereon.

The nature of my invention consists in a series of mechanical devices, which can only be understood by reference to the specification and drawings.

To enable others skilled in the art to make and use my invention, I will proceed to describe its construction and operation.

Drawings.

Figure 1 is a perspective view of my machine.

Figure 2 is an elevation of a part of the machine.

Figure 3 is a vertical section of the same.

Figure 4 is a section showing in detail a part of the stringing-device.

Figure 5 represents the compressing-jaw and eyeletting-device in part.

Figure 6 shows one of the tags as prepared by the cutting-machine.

Figure 7 is a detail of part of the stringing-device.

I use, in connection with this machine, an automatic feeding-machine, which takes the tags, in the condition that the cutting-machine leaves them, that is, cut, punched, and partly folded, as shown in fig. 6, and places them between the jaws H^3 and H^4 , figs. 5 and 1; or, if desirable, the tags may be fed in by hand.

A B C represent the frame, to which the other parts of my machine are attached.

D represents the main or operating-shaft of the machine.

H, figs. 1 and 3, is a cam, which, operating through the bent lever H^1 , actuates the eyelet-punch H^2 , and through it the compressing-jaw H^3 .

O, fig. 1, is a cam, which, operating through the stud O^1 on the standard O^2 , presses down one end of the lever O^3 , which action throws up the eyelet-spindle O^4 .

The eccentric F, fig. 1, acting through the rod F^1 and rocker-shaft $F^2 F^3$, operates the glue-carrier F ^{4} .

F ^{6} , fig. 1, is a trough for holding the glue, which may be kept warm by the use of steam, or otherwise.

F ^{5} is a roller, which just touches the upper surface of the glue, and is so arranged that the glue-carrier F ^{4} comes in contact with it at each vibration, and taking some of the glue, carries it to the tag, which is between the compressing-jaws H^3 and H^4 .

E, fig. 1, is a crank-arm, attached to the main shaft, which, acting through the link E ^{1} , causes the wheel E ^{2} to oscillate.

E ^{3} , E ^{4} , and E ^{5} , are cords, attached to the wheel E ^{2} , and so arranged, in connection with small guiding-pulleys, that at each oscillation of the wheel E ^{2} , they will give a reciprocating motion to the bar E ^{6} , figs. 1 and 4.

The nipper E ^{7} is provided with a spring, so that it is self-closing, and is only opened by coming in contact with the hanger E ^{8} , fig. 4, or with the arch E ^{9} , fig. 1. Thus it opens to receive the string, at P, fig. 4, and having seized it, draws it past the eyeletting-device, and releases it when E ^{1} , fig. 4, is depressed by coming in contact with the arch E ^{9} , fig. 1.

K, figs. 1 and 3, is a cam, which operates the bar K'. This bar or needle K' is forked, as shown in plan, fig. 7, so that it may pass the string S into the orifice S' made for that purpose in the card, fig. 6, and beyond the eyelet-holes, so that when the eyelet is in place, the string is securely fastened.

N ^{1} N ^{3} N ^{6} , fig. 2, is the eyeletting-device, and is similar in its construction and operation to the one described in J. F. Sargent's Letters Patent, dated January 5, 1864, and numbered 41,125; and hence does not require particular description.

The eyeletting-tube N ^{3} N ^{6} is pushed downward and forward by the bent lever N ^{4} , which is operated by the cam N ^{5} .

The circular eyelet-box N ^{1} is revolved by the start N, on cam O, fig. 2, coming in contact with the toothed wheel N ^{2} .

The lever L ^{1} L ^{2} , fig. 3, serves to depress the string S, fig. 5, and bring it in such a position that the bar K', in its forward motion, will contact with it, and carry it forward into the tag, as has been already described.

M ^{1} M ^{2} , figs. 2 and 4, are shears, which serve to cut off the string, and are operated by the cam M ^{3} and the lever M.

The end of the link E ^{1} is provided with stud and set-screw R, fig. 1, the stud passing through the slot R' made in one of the spokes of the wheel E ^{2} , the whole arranged so that the stud may be adjusted in the slot R', thus regulating the motion given the wheel E ^{2} by the link E ^{1} ; and as the motion of the string-carrier E ^{6} depends upon the motion of the wheel E ^{2} , it will be seen that the length of the string may be regulated at pleasure.

The operation of my machine may be set forth as follows:

The tag, as it leaves the cutting-machine, appears as shown in fig. 6, that is, it is cut, punched, and bent as shown. It is now placed between the jaws H ^{3} H ^{4} , and the fold is covered with glue by the glue-carrier F ^{4} . Then the compressing-jaw H ^{3} compresses the fold downward on to the body of the tag. While this operation is going on, the string-carrier takes the string S and carries it by the end of the fork-bar K'. The bar

K' then carries the string forward through the opening S' in the tag, as shown in fig. 6, after which the eyelet is inserted and riveted down by the eyeleting-device, that completes the operation.

What I claim as my invention, and desire to secure by Letters Patent of the United States, is—

1. The combination of the glue-feeding device F³ F⁴ with the glue-roll F⁵, operating substantially as described, and for the purpose set forth.

2. The combination and arrangement of the eyeleting-punchers O¹ H² and the compressing-jaws H³ H⁴,

working substantially as described, and for the purpose set forth.

3. The bar K', in combination with the levers L¹ L², when used for passing the string S forward into the fold of the tag, operating substantially as described, and for the purpose set forth.

4. The string-carrier E⁶ E⁷, operating substantially as described, and for the purpose set forth.
